(57) **CLAIM**

The ornamental design for a race car simulator frame, as shown and described.

DESCRIPTION

FIG. 1 is a perspective view taken from the top and front of a race car simulator frame showing my new design;

FIG. 2 is a left side elevational view of the race car simulator frame showing my claimed design, the right side elevational view being the mirror image thereof;

FIG. 3 is a top view of the race car simulator frame;

FIG. 4 is a bottom view of the race car simulator frame;

FIG. 5 is a front view of the race car simulator frame; and,

FIG. 6 is a rear view of the race car simulator frame.
